CLAIM

I claim the ornamental design for an automatic voltage regulator, as shown and described.

DESCRIPTION

FIG. 1 is a front, right, top perspective view of an automatic voltage regulator.

FIG. 2 is a top view of the automatic voltage regulator of FIG. 1.

FIG. 3 is a bottom view of the automatic voltage regulator of FIG. 1.

FIG. 4 is a rear view of the automatic voltage regulator of FIG. 1.

FIG. 5 is a front view of the automatic voltage regulator of FIG. 1.

FIG. 6 is a left view of the automatic voltage regulator of FIG. 1; and,

FIG. 7 is a right view of the automatic voltage regulator of FIG. 1.

Any broken lines in the figures illustrate portions of the automatic voltage regulator that form no part of the claimed design.
